CLAIM

The ornamental design for an automatic climate control unit for mounting on automobile dashboards or floors, as shown and described.

DESCRIPTION

FIG. 1 is a front perspective view of an automatic climate control unit for mounting on automobile dashboards or floors showing our new design;

FIG. 2 is a front elevational view thereof, on a reduced scale;

FIG. 3 is a right side view thereof, on a reduced scale;

FIG. 4 is a top plan view thereof, on a reduced scale;

FIG. 5 is a left side view thereof, on a reduced scale;

FIG. 6 is a rear elevational view thereof, on a reduced scale; and,

FIG. 7 is a bottom plan view thereof, on a reduced scale.

The bottom stalk of the climate control unit has been shown broken away in FIGS. 1-7, to indicate indeterminate length.
